WAGON DRILL

Thomas L. Murphy, Athol, Mass., assignor to
Worthington Pump and Machinery Corporation,
New York, N. Y., a corporation of Virginia

Application February 3, 1934, Serial No. 709,578

5 Claims. (Cl. 255—51)

This invention relates to rock drill equipment and more particularly to drilling apparatus adapted to be mounted on vehicle frames and known specifically in the art as wagon drills.

5 The invention comprises in brief, a frame having a substantially vertical tower acting as a guide for a rock drill mounting, and wheels secured to the frame to permit the device to become readily portable. In the present construction the 10 tower comprises a relatively high pair of columns adapted to serve as a guide for comparatively long drill steels. The present invention is directed to means whereby the angle of the drill steel can be accurately maintained, and comprises adjusting mechanism in the vehicle chassis, acting 15 on the chassis supports to compensate for irregularities in the rock face or bench, and without resort to wedges or blocks placed under the supports.

20 Means are provided also whereby the associated rock drill may be readily detached from the mounting or slab back, and to novel construction of the guide means.

One of the objects, therefore, of the present 25 invention is to provide means whereby the wagon drill may be adjusted so that the drill steel may be maintained at or adjusted to a predetermined angle.

A second object is to provide a construction 30 whereby the drill-angle control means may readily and positively change the position of the drill guide without detracting from the rigidity and strength of the chassis.

A further object is to provide simplified construction whereby the rock drill may be slidably mounted in a guide, possessing ease of adjustment, and which facilitates the interchangeability of the rock drill to suit the requirements 35 of the work.

40 With these objects in view, the invention consists of various features of construction and combination of parts, which will be first described in connection with the accompanying drawings showing a wagon drill of the preferred form embodying the invention, and the features forming the invention will be specifically pointed out in the claims.

Other objects and advantages will become apparent from the following description in conjunction 45 with the accompanying drawings, in which:

Fig. 1 is a side elevation of a preferred form of the wagon drill.

Fig. 2 is an enlarged section taken on lines 2—2 of Fig. 1.

Fig. 3 is an end view of the wagon drill.

Fig. 4 is a cross section taken on the lines 4—4 of Fig. 1.

Fig. 5 is a longitudinal cross section of the rock 5 drill mounting or slab back taken on the lines 5—5 of Fig. 6.

Fig. 6 is a front elevation of the slab back.

Fig. 7 is a cross sectional view taken on the lines 7—7 of Fig. 6.

The wagon support for the rock drill comprises a chassis 10 and comprises in the preferred form 10 a frame 11, a bracket 12, and a beam 13. The bracket 12 is shown secured to a pair of transverse channels 14, mounted on the frame 11 at approximately its mid-section. The beam 13 is a rigid member of any suitable construction, such 15 as a pair of channel bars or a hollow box spar, and is pivotally connected at one end as by bolt or pin 15. At the opposite extremity, provision is made for a vertical swivel pin 16. The bottom 20 of the swivel is rigidly secured to a fork 17, which serves as a mounting means for the front wheel 18. A fifth wheel 19 is provided at the intersection of the fork and at bottom of the beam 16 to take the upward thrust of the wheel and to facilitate the swivel action. A pair of rear wheels 20 are mounted to the frame 11 in any conventional manner. A handle 21, mounted to a yoke 22 on the fork 17, serves as a means to guide the vehicle to the desired location for operation.

Projecting upward from the rear end of the 30 frame 11, and preferably at right angles to it is a tower 23, and comprising in the preferred form a pair of channel members or guides 24. A pair 35 of tower supports 25 extend as a bracket from the tower 23 to the front end of frame 11. A plurality of transverse members or rungs 26 connect the two supports and form, in effect, a ladder to enable operators to make adjustments to the rock drill at any point on the tower. A pulley 27 is rotatably mounted at the upper extremity 40 of the channel members 24. Near the bottom of tower 23, and substantially parallel with frame 11 is a platform 28 upon which is mounted a hoist 29 of any conventional design. An air winch is shown in Fig. 1, but a manually operated 45 cable 30 extends from the hoist upward around pulley 27 and continues downward to the rock drill mounting means to be described later.

Wheel-elevating or drill-angle control means 50 is provided and comprises a guide bracket 31 rigidly secured to the frame 11 as by longitudinal angles 32 and transverse channels 33. The inner distance between the legs of the bracket conforms closely with the outer width of the beam 55

13, permitting the beam to travel vertically with a minimum amount of play. To effect the close match of these two parts a plurality of spacers or reinforcing sleeves 34 are secured inside the beam 13 by means of clamp bolts 55, passing thru slots 56 in the sides of the beam 13. The bolts 55 also hold the clamp 57 in position. Suspended from the top of the inverted bracket 31 is a threaded rod 35, provided with a shoulder 36 beneath the bracket, and a handle or crank 31 having a collar 38 above the bracket. The threaded rod 35 is free to rotate in the guide bracket, the vertical thrust in both directions being taken by the shoulder 36 and the collar 38. Secured to the beam 13 and in alignment with the threaded rod 35 is a follower 39 internally threaded to correspond with the thread on the rod 35. By this construction the beam may be lowered or raised at will following the rotation of the threaded rod 35 turned by the handle or crank 37.

The slab back or drill mounting means is best seen in Figs. 5, 6, and 7, of the drawings. In the present art the term "slab back" designates a weighted drill feed assembly and its use throughout this application will be identified with this type of construction. The slab back comprises a cradle or feed slide 40 provided with vertically-aligning holes 41, adapted to receive through-bolts 42 which correspond with mounting means provided in the rock drill (not forming part of this invention) indicated by broken lines in Fig. 5. As shown in Fig. 5, the cradle 40 is shaped to conform closely with the contour of the drill. A pair of longitudinal lugs 43 extend the length of the cradle and serve as a means to align and mount the drill and cradle assembly in proper relation to the slab back. A pair of drill clamps 44 are held to the slab back bed 45 by means of a plurality of cap screws 46. When these bolts are tightened the drill clamps 44 tightly engage the longitudinal lugs 43 and bind them firmly in the slab back bed 45. The slab back bed is mounted closely adjacent and parallel with the outside of the flanges of the channels 24. The slab back guide 41 is rabbeted on either side as at 48 to conform closely with the inner, beveled edge of the channel flanges, but is spaced sufficiently from them to provide for free sliding action with a minimum amount of play. The slab back guide is held to the bed 45 by means of a plurality of through-bolts 49. The entire slab back assembly is supported by the cable 30 passing around a grommet 50, held in a slot in the slab back bed 45, by means of a pin 51. The pressure applied to the drill steel is supplied by the weight of the rock drill and its associated slab back, and may be augmented as desired by the addition of feed weights 52 shown in Figs. 5 and 6 at the top of the slab back, straddling the cable and being held to the slab back bed by means of studs 53. The entire slab back may be rigidly secured to the channel members 24 to facilitate portability, by the use of locking bolts 54 which are removed when the drill is set for operation.

In operation, the wagon drill is transported to a selected site, the handle 21 being used both as a draw bar, and as a steering rod to turn the front wheel 18 about its swivel mounting. If desired the wheels may be replaced by skids or any other suitable chassis supports. Flanged wheels adapted for use on tracks similarly may be employed without departing from the scope of the invention. When the wagon has been located at

the site of operation, the slab back is hoisted to the top of the tower 23 by means of hoist 29 which is preferably operated by compressed air. Any necessary substitution or adjustment of the drill steel is made, after which slab back and drill, as a unit, are permitted to descend until the steel bit engages the rock face or bench. The angle of the drill rod can be adjusted by rotating the handle 37 of the elevating mechanism in the proper direction. If the rod 35 is provided with right hand threads, rotating the handle 37 in a clockwise direction when looking from the top will cause the follower and beam 13 to rise in the guide bracket 31, secured to the frame 11. Expressed in other words, the bracket 31 secured 15 to the front end of the frame 11 will descend with respect to the beam 13. Referring to Fig. 1, it will be seen that by lowering the front end of the frame 11 with respect to the beam such as will be produced by clockwise movement of the 20 handle 37, will cause the beam to move about its pivot 15, and the tower will become tilted in a counter-clockwise direction about wheel 20, thereby varying the angle of the guide with respect to the vertical. To adjust the drill rod 25 to an angle either on the left side or the right side of the vertical, it will simply be necessary to turn the handle 37 in a clockwise or counter-clockwise direction respectively. When the tower is being moved in a clockwise direction the 30 thrust is taken up by the shoulder 36 at the top of the guide bracket 31. If desired, greater rigidity may be obtained by tightening the clamp bolts 55, after the proper angular adjustment has been made.

After the proper angular adjustment has been made, the apparatus will be ready for operation, the rock drill preferably being actuated by air supplied through the conventional flexible hoses (not shown).

When it is desired to substitute rock drills as may become necessary by a change in working conditions or material, the substitution may be effected by merely removing the two bolts 42, releasing the rock drill from the cradle. The operation is reversed when installing the new rock drill. The slab back unit slides along the flanges of commercial channels which do not require special machining or surfacing for satisfactory operation.

The wagon drill is shown provided with a three wheel support as it has been found easier to obtain a solid setting on an uneven surface when three wheels are used than when four wheels are used, but it is understood that the invention is not to be limited to a three wheeled construction. Flanged wheels may be employed, in which case four wheels would be preferable. In this instance, the swivel arrangement could be dispensed with, and the beam 13 would extend to both front wheel supports. In Fig. 1, the portion of the vehicle to the left has been described as the front, and the portion to the right as the rear; the tower has been shown mounted at the rear. I may transpose the wheels so that the tower is adjacent the end 65 having but one wheel and supply two wheels as support for the opposite end, without departing from the spirit of the present invention. I may also provide the beam 13 in any position best adapted to the working conditions and to the 70 relative dimensions of the associated parts. Thus though the beam is shown in the preferred embodiment as being pivotally mounted above the frame 11, it may be supported with equal advantage either below the frame 11 or on a level with 75

it, corresponding compensation being made in the elevating mechanism.

As described, the angle adjusting mechanism comprising the beam 13 and the elevating mechanism provides for a deviation in the angle of the tower within appreciable limits predicated upon the relative proportions of the parts. By employing a threaded rod and a handle to rotate the rod, this angle may be varied by small increments. The elevating mechanism, rather than tending to weaken the chassis, strengthens it by providing reinforcement at a point at which it is normally subjected to the greatest stress, to wit, near the mid-section. The elevating action is positive and direct, and no extra locking means are required. A large portion of the chassis, comprising the frame 11, the tower support 25, the stand 28, and the hoist 29, for all general purposes, are all integral with the channel members 24, forming the guide for the slab back. Their combined moment of inertia will oppose any sudden shocks produced by the slab back and will tend to minimize vibration and oscillation of the tower structure 23.

It will be understood that the invention is not to be limited to the specific construction or arrangement of parts shown, but that these may be modified widely within the invention defined by the claims.

What is claimed is:

1. In a wagon drill, a chassis including a frame, supporting means for said frame, a beam pivotally mounted with respect to said frame, supporting means for said beam, a tower secured to said frame and substantially perpendicular to it, drill mounting means carried by said tower and comprising a guide member, a bed secured to said guide member, said guide member being free to slide with respect to said tower, a drill cradle secured to said bed, a rock drill detachably carried by said cradle and adjustable means connecting said beam and said frame for regulating the angle of said tower.

2. In a wagon drill, a chassis including a frame, a tower at one end of said frame and perpendicular thereto, supporting wheels attached to the frame at the end adjacent said tower, a beam pivotally connected to said frame, a supporting wheel carried by said beam, a guide member slidably carried by said tower, means for detachably mounting a rock drill on said guide, means for moving said slide member along said tower, and adjustable means connected to said beam

and said frame for adjusting the elevation of the beam carried supporting wheel for regulating the angle of said tower.

3. In a wagon drill, a chassis including a frame, a pair of supporting wheels at one end of said frame, a tower connected to said frame at the end adjacent to said supporting wheels, drill mounting means slidable along said tower and comprising a guide member, a drill cradle carried by the guide member, means connected to said guide member for moving it along said tower, a beam pivotally connected to said frame, a swivelly mounted supporting wheel carried by said beam, adjustable means connected to said beam and to said frame for adjusting the elevation of said swivelly mounted supporting wheel with respect to the frame for regulating the angle of said tower.

4. In a wagon drill, a chassis, said chassis having a frame, supporting means for said frame, a beam pivotally mounted with respect to said frame, supporting means for said beam, a tower secured to said frame and substantially perpendicular to it, said tower comprising a plurality of structural columns, drill mounting means comprising a guide member, a bed, said guide member and said bed being secured one to the other, said guide member being rabbeted to conform with longitudinally extending projections on said columns and being free to slide with respect to said columns, a drill cradle secured to said bed, fastening means connecting with said cradle and being adapted to detachably mount a rock drill to said cradle.

5. In a wagon drill, a chassis, said chassis having a frame, supporting means for said frame, a beam pivotally mounted with respect to said frame, supporting means for said beam, a tower secured to said frame and substantially perpendicular to it, said tower comprising a plurality of structural columns, drill mounting means comprising a guide member, a bed, said guide member and said bed being secured one to the other, said guide member being rabbeted to conform with longitudinally extending projections on said columns and being free to slide with respect to said columns, a drill cradle secured to said bed, fastening means connecting with said cradle and being adapted to detachably mount a rock drill to said cradle, and adjustable means intermediate said beam and said frame for regulating the angle of said tower.

THOMAS L. MURPHY.
